UNITED STATES PATENT OFFICE

153,434

DESIGN FOR A TIRE

William F. Hoelzer, Greensburg, Pa.

Application April 29, 1947, Serial No. 138,667

Term of patent 14 years

(Cl. D90—20)

To all whom it may concern:

Be it known that I, William F. Hoelzer, a citizen of the United States of America, residing at Greensburg, in the county of Westmoreland and Commonwealth of Pennsylvania, have invented a new, original, and ornamental Design for Tire, of which the following is a specification, reference being had to the accompanying drawing, forming part thereof, in which:

Figure 1 is a side elevational view of a fragmentary portion of a tire showing my new design, the other portions of the tire being of similar design and appearance and being broken away and removed, and the tire outline being indicated partly in broken lines;

Fig. 2 is a plan view looking in the direction of arrow A, showing a fragmentary portion of one shoulder of the tire;

Fig. 3 is a sectional detail showing a fragment of the tire shoulder taken substantially on the line 3—3 of Fig. 1 and enlarged with respect to that figure;

Fig. 4 is another sectional detail showing a fragment of the tire shoulder taken substantially on the line 4—4 of Fig. 1 and enlarged with respect to that figure;

Fig. 5 is a transverse sectional view with parts broken away and removed, taken radially through

the tire substantially along the line indicated at 5—5 of Fig. 1;

Fig. 6 is a fragmentary detail view showing a single medallion of the design from the viewpoint used in Fig. 1 and enlarged with respect to that figure; and

Fig. 7 is a fragmentary detail view showing a single medallion of the design from the viewpoint used in Fig. 2 and enlarged with respect to that figure.

The characteristic features of my design reside in the portions shown in solid lines.

I claim:

The ornamental design for a tire, substantially as shown and described.

WILLIAM F. HOELZER.
